Attorney.

UNITED STATES PATENT OFFICE.

HEINRICH PÖSENTRUP, OF MUNSTER, GERMANY.

GRIPPER BRAKE FOR RAILWAYS.

Application filed February 11, 1925, Serial No. 8,515, and in Germany February 19, 1924.

My invention is illustrated diagrammatically and by way of example in the accompanying drawings, in which Fig. 1 is a longitudinal section through one of the constructional forms in which my invention may be embodied, Fig. 1^a and Fig. 1^b being diagrammatic sections through the braking mechanism and the wheel to be braked thereby, Fig. 1^a showing the wheel in engagement 5 with the brake and Fig. 1^b showing the wheel out of engagement with the brake, Fig. 2 is a cross-section of Fig. 1, the movable parts being shown in their working position, Fig. 3 shows said movable parts in position of rest 10 and Fig. 4 is a section in the plane A—A of Fig. 3.

This invention relates to a gripper-brake for railways having brake-rails which may be raised and lowered. It is known that railway vehicles may be braked by pressing a pair 20 of brake-rails or the like with a relatively great force against the tyres of the wheels. A strong braking action can in this case be obtained, if, for instance, a wedge is pressed 25 into a wedge-shaped opening or if a wedge-shaped opening is pressed around a wedge. If, for instance, a member 1 as shown in Fig. 1^a is pressed by means of a force R which acts in upward direction with its wedge-shaped opening against a wedge-shaped body having a weight R, the wedge-shaped body 30 will be lifted from its supporting member, for instance a rail, and a braking force D will be generated in horizontal direction, said 35 force D depending upon the weight R and of the angle of the wedge. The braking forces will become ineffective, as soon as the member 1 is lowered to the extent shown in Fig. 1^b. The action of the present gripper-brake for railways is based upon the operations as diagrammatical indicated in Figs. 1^a and 1^b.

The lifting wheels causing the lifting and lowering of the brake rails have been fully described in my copending application for patent application Serial No. 4,073. According to this, for instance, a bridge-shaped construction which carries the slides and the brake rails is mounted upon rollers r as shown 50 in Fig. 1 in such a manner that the entire construction may be moved forwardly and backwardly in the direction of the railway track by means of the force K as also indicated in Fig. 1. This force K may be furnished by 55 an electric motor or pressure cylinder or the like which is not indicated in the drawing.

If the rollers r are pressed upon the inclined surfaces of supporting members t, the brake will be lowered by the amount u, if it is moved towards the left by a distance v, as indicated by dotted lines on the lefthand-side of Fig. 1. In this case the railway vehicles may move without impediment through the brake along the track, while in lifted position of the brake each wheel of the vehicle which moves from the right-hand side to the left-hand side will be lifted and braked thereby. If the brake is lifted so as to act against the load of the railway vehicle, a braking action will take place tending to move the brake-rails together with the entire braking mechanism towards the right-hand side. On the other hand the vertical load of the vehicle tends to move the brake downwardly upon the inclined surfaces of the supporting members t that is to say, the brake will be moved towards the left-hand side. These two forces will approximately counteract each other and the brake may therefore be lifted and lowered with only a small expenditure of power.

On the drawing c and d denote the brake-rails, e denotes the ramp-rail, and a and b denote reinforcing-girders for and of said rails c d e. k denotes triangular members supported in pairs by transverse base-plates 1 and having each an oblique face i upon which is supported a counter-plate pertaining to one of the gripper-members f and g. In Fig. 2 the gripper f g is shown in its braking position, in which its members f and g are kept depressed by the weight of a car just running over the gripper brake. The operative members are so dimensioned and arranged relatively to one another that wheels having the smallest normal tyre as well as the lowest tread are lifted off the rails for about 1 cm. With wheels having the broadest tyres and the highest treads existing, the lifting height will increase to about 3 cm.

The base-plate l is somewhat shiftable in its longitudinal direction and its movement is limited in both directions by angular abutment members. Fig. 2 shows the base-plate in one of its two end-positions, Fig. 3 in the other.

The triangular members k have downwardly directed extensions m which are located between two parallel transverse girders n n. The grippers f and g are also located in the gap between these girders. There are shown in Fig. 1 three pairs of girders n n, and there

are, therefore, also three pairs of grippers. The two members forming a pair are connected with one another by a bolt *o*, the ends of which can slide vertically in a slot *s* of two guide-members *p*, *p* secured to the bottom-faces of the said girders. The length of the slots *s* is such that there is sufficient play for the bolt *o* to follow the vertical movements of the grippers when their position changes from that in Fig. 2 to that in Fig. 3, and reversely, and this guiding insures the bolt *o* against accidental cross movements.

When the brake is lifted but not yet loaded by the car wheels, the bolt *o* rests on the lower part of its guide and accordingly the two gripper arms occupy a somewhat lower position and the opening between the brake rails is then somewhat smaller as shown in Fig. 2.

When now a car enters into the brake the wheels press the brake rails away from each other. Since the gripper arms are firmly connected with each other at their under portion by means of the bolt *o*, during pressing apart of the brake rails the bearing plates *h* provided on said gripper arms must slide upon the oblique faces *i* of the supports *k* mounted on the base plate *l*, thus lifting the entire gripping device into the position as indicated in Fig. 2 and the ramp rail assumes such a high position, that the wheels are lifted from the track rails. The bolt *o* now does not rest any more in its guide and the vertical weight, effected by the wheels, results therein that said wheels are clamped in accordance with the wedge angle, formed by the supporting plates *i*.

When the car is sufficiently braked, the brake is laid down to the position according to Fig. 3. During lowering of the brake the angle of the gripper arms will not be changed until the wheels have come in contact with the track rails. As soon, however, as said wheels contact with the rails, the ramp rail *e* is loosened from the wheel tyre and the braking operation ceases. The loaded grippers now descend further with the whole

structure, the foot of the girder *a* sliding on the guide *q* and pressed away by the lower inclined part of said guide from the track rail, until the position according to Fig. 3 is reached. At the same time the gripper arm *g*, which is connected with the gripper arm *f* by the bolt *o*, is laid down outwardly, as far as the wedge plate *i* will permit. In the position according to Fig. 3 the bordering space of the vehicle is free.

The members *m*—*l* appear in different positions in Figs. 2 and 3 because the base plate *l* on which these parts are mounted is somewhat shiftable as above indicated. In operative condition of the brake, according to Fig. 2, the base plate *l* will be maintained in the position as shown by means of the car wheel. If, however, the brake is in inoperative condition, as shown in Fig. 3, the plate *l* will be kept in its outermost left-hand position by means of a spring (not shown). The gripper-arm *g* is provided with an abutment-plate *q*¹. When the brake-rails are being lifted below a car, no guide like *q* or *q*¹ is required, but if they are lifted without load, as is the rule, the abutment members keep the brake-rails so much off the track-rail that the cars run securely into the brake.

I claim:

A gripper-brake for railways, comprising, in combination: liftable brake-rails; grippers consisting each of two members and having said brake-rails secured to them; a ramp-rail also secured to said grippers; members located laterally from the gripper arms and having each an oblique face adapted to serve as support for one of the gripper-arms; these latter being adapted to slide upon said oblique face and to be depressed by a car running over the brake; means carrying the said lateral members, and transverse girders supporting said means; and means permitting vertical movements of said grippers, substantially as set forth.

In testimony whereof I affix my signature.

HEINRICH PÖSENTRUP.
